Primary Examiner — Lakiya G Rogers*Assistant Examiner* — Julice Seung Eun Oum(57) **CLAIM**

The ornamental design for an exercise equipment as shown and described.

DESCRIPTION

FIG. 1 is a front, right and top perspective view of an exercise equipment showing my new design;

FIG. 2 is a front, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged partial view of FIG. 1; and,

FIG. 10 is an enlarged partial view of FIG. 2.

The broken lines in the figures illustrate portions of the exercise equipment that form no part of the claimed design. The dot-dash broken lines are boundary lines that are included for reference purposes only to identify the enlarged views and form no part of the claimed design.
